UNITED STATES PATENT OFFICE.

CARL F. BRAUN, OF PASADENA, CALIFORNIA.

CONDENSER, COOLER, AND ABSORBER.

Application filed February 7, 1923. Serial No. 617,493.

This invention relates to a condenser, cooler and absorber of the general type indicated in my copending application entitled Condenser, filed June 29, 1921, and bearing the Serial No. 481 287, the condenser in that instance being of the vertical type, while in the present case the structure is of the horizontal two-pass type.

It is the principal object of the present invention to provide a tubular horizontal condenser in which a desired ratio of condensate cooling surface to vapor condensation surface is obtained, and in which there will be no possibility for the condensate to escape without being properly cooled.

The present invention contemplates the construction of a condenser having a cylindrical horizontally disposed shell inclosing a longitudinally extending tube nest which tubes are divided into two parallel groups by a central partition wall extending substantially the length of the shell, the shell being fitted with spaced transverse baffle members so constructed and arranged as to impart turbulence to vapors flowing through the shell and so proportioned that a proper ratio of condensing surface and condensate cooling surface will be established throughout the length of the condenser.

The invention is illustrated by way of example in the accompanying drawings, in which:

Fig. 1 is a view in longitudinal section through a battery of condensers embodying the present invention.

Fig. 2 is a view in transverse section through one of the condensers showing the manner in which equalization of cooling and condensing surfaces is brought about, and also disclosing the means by which the passageways within the shell are separated.

In considering the present invention it is to be borne in mind that these condensers are especially adapted for use in oil refining and similar industrial processes, where the usual steam condenser used as a vapor condenser has proven a failure. This is due to the fact that the ratio of condensate cooling surface to condensation surface is insufficient with the result that the condensate is not cooled to a low temperature, and for the added reason that the vapors and fluids stratify in the circulating tubes. This is overcome in the present case by constructing a condenser having an outer cylindrical shell

10 inclosing a tube nest 11. This tube nest is rigidly secured at one end of the shell and communicates with a head 12. The head is fitted with a pair of ports, one conducting a cooling medium to the tubes and the other one carrying it away from the condenser after it has circulated the length of the condenser and has returned. Vapors are admitted through an induction passageway 13 and pass from the condenser through education passageway 14. The shell is centrally divided by a horizontally extending partition 15, which partition extends from a point of abutment against the fixed tube sheet to a terminating point near the opposite end of the shell. Referring to Fig. 2, it will be seen that the partition is formed by a plurality of relatively thin spaced plates. These plates are of greater width than the diameter of the shell and extend into diametrically opposite grooves in the wall of the shell. By this method the effect of so-called labyrinth packing is obtained so that fluids will not readily pass from passageway A to passageway B, except at the end of the partition.

The passageways A and B are interrupted at equal intervals throughout their lengths by transverse baffle plates 16 which are of an outside diameter substantially equal to the inside diameter of the shell. These baffle plates are formed with openings 17 through which the tubes and the vapors pass and by which the vapors are given a turbulent action. This will insure that the fluids within the shell will be thoroughly agitated and that they will come into intimate contact with the cooling surfaces to ensure a high degree of absorption effect due to the fact that the baffle plates are formed with openings through which the vapors must pass and by which turbulence will be created in the flowing stream of vapor, thus agitating the vapor in a manner to disturb its flow and to recurrently bring the vapors into contact with the cooling surfaces.

In order to insure that the condensate may be cooled to a desired low temperature, the baffle plates may be designed to form dams. As seen in Fig. 2 of the drawings, each of the baffle plates 16 is formed with a plurality of openings 17 through which vapors may pass, and in the edge of which openings cooling tubes 11 are positioned. By eliminating the vapor openings along the portions of

the baffle plates adjacent the partition 15 and the lowermost portion of the shell wall, it will be seen that permanent dams will be formed by a part of the baffle plates, and that a predetermined number of cooling tubes will extend through the baffle plate portions which act as dams. Thus condensate accumulating between the transverse baffles will flow onto the partition 15 in passage-way A or onto the floor of the shell in passageway B. When there is an excess accumulation of condensate, its level will reach the lowermost rows of openings 17 in the baffle plates and will overflow into the next succeeding space between the baffle plates. This overflow will continue until the last baffle plate in the upper passageway A has been reached when the condensate will overflow the baffle plate indicated as 16' in the drawings, and will flow onto the bottom of the shell forming the floor of the return passageway B. The condensate will gradually overflow the dams formed by the successive baffles, and will eventually be drained out through the drain 14 and be drawn off through a suitable trap not shown in the drawings. These dams will impound the condensate which is formed between the baffle plates and will cause it to accumulate to such a depth as is required to immerse a desired number of cooling tubes, thus presenting a required area of cooling surface to the volume of condensate which will accumulate. Thus in the design of the structure, a definite ratio of condensate cooling surface and vapor condensing surface may be determined, and by the construction of the baffle plates and the distribution of the tubes, this ratio may be constantly maintained during the operation of the apparatus. Attention is directed to the fact that in ordinary condensation systems using steam boxes and the like, the condensate accumulates in large volumes and is entirely out of proportion to the amount of cooling surface provided, and thus does not have the opportunity to receive the maximum cooling effect derived from more intimate contact with the large area of surface of the cooling tubes as provided in the present instance. Furthermore by the present arrangement, the surface of the cooling tubes may be apportioned for use in bringing about a condensation action of the vapor and for cooling the condensation, these apportionments being in proper ratio to insure a maximum condensation, cooling and absorption action.

In operation of the present invention the condenser is assembled as shown in the drawing, and a vapor admitted to the shell through inlet passageway 13, thereafter travelling the length of the shell along passage A. During this time the vapors will pass through openings in the various trans-

verse baffle plates, at the same time circulating around and along the cooling tubes. This will bring about a partial condensation of vapors which condensate will fall onto the longitudinal partition 15. The portions of the baffle plates adjacent the longitudinal partition are so designed as to cause a desired accumulation of condensate between the baffles thus submerging the lowermost tubes. The uncondensed vapors will flow the length of the shell, thereafter passing around the end of the partition 15 and returning along the lower passageway B. This passageway is also designed to insure that the condensate will be impounded at intervals and a desired cooling effect produced. Attention is directed to the fact that the vapors passing along the upper passageway A will be confined within this passageway until they reach the end thereof, and that the partition will act as an effective barrier between passageways A and B. This action is brought about due to the fact that the vapors would have a circuitous path of travel in order to pass around the edges of the partition plates and across the series of plate grooves in the opposite faces of the shell. The leakage will also be further resisted by the counter pressure of fluid which may accumulate in the space between the plates of the partitions since the fluid trapped between the plates and the longitudinal partition will tend to form a seal in the joint between the partition plates and the shell wall, and will in the case when viscous liquids are used, cause a body of liquid to be created between the two passageways of the shell, and which liquid will have a lower temperature than that of one passageway and a higher temperature than that of another passageway due to its intermediate position. Its viscosity will, therefore, tend to prevent the flow of the liquids and at the same time will form a body of liquid having a temperature intermediate of the liquids in the two passageways, thus tending to prevent appreciable transfer of heat from one passageway to the other.

It will thus be seen that the invention here disclosed provides suitable means for insuring that a proper proportion of condensation cooling surface will be maintained in relation to the condensing surface and also in relation to the condensate, and it will be further seen that the partition construction here embodied insures that there will be substantially no leakage of vapor between the passageways of the condenser.

While I have shown the preferred form of my invention as now known to me, it will be understood that various changes might be made in the combination, construction and arrangement of parts by those skilled in the art, without departing from the spirit of the invention as claimed.

Having thus described my invention, what I claim and desire to secure by Letters Patent is:

which vapors and liquids an absorption action will take place.

40

1. A condenser comprising an outer shell extending horizontally, a central longitudinally extending partition wall forming parallel passageways within said shell, a tube nest comprising two groups of tubes, one extending longitudinally of each passageway, and transverse baffle plates having imperforate portions for maintaining a direct ratio between the cooling and condensing surfaces.

3. In a heat exchanger, or like structure, a longitudinal partition forming parallel passageways within the shell, said partition comprising a pair of parallel spaced plates, grooves formed in inner face of the partition wall for separately receiving the edges of said plates, whereby the plates will create a substantially tight joint with the wall of the shell and will form a dead fluid space between the plates.

45

2. A heat exchanger comprising an outer shell, a pair of parallel passageways within said shell communicating with induction and exduction ports at one end of the shell and with each other at the opposite end of the shell, a tube nest extending longitudinally of both passageways and through which a cooling medium may flow in a counterdirection, transverse baffles disposed across the passageways at intervals throughout the lengths of the tubes and through which the tubes extend, and openings through said baffles for permitting vapors to pass through the shell and for imparting turbulence to the vapors, said openings being arranged a predetermined distance above the floors of the passageways so that portions of the baffle plates will act to impound the condensate accumulating between adjacent baffle plates and cause it to accumulate to a desired level and to submerge a predetermined area of cooling surface in the condensate, whereby the condensate will be cooled and an exposed area of liquid will be provided over the surface of which the vapors pass, and between

4. In a heat exchanger, or the like, having a shell, a removable longitudinally extending partition therein, said partition comprising a pair of parallel plates spaced a relatively small distance apart, the shell being formed with longitudinally extending parallel grooves along the inner face of its side wall and along which the edges of said partition plates may be slidably positioned.

50

5. In a heat exchanger, or like structure, a tube nest extending longitudinally thereof and slidably positioned therein, a partition wall structure carried with said tube nest, whereby the tubes of the nest will be divided into groups and the interior of the shell will be divided into longitudinally extending parallel passageways, said partition structure comprising parallel plates spaced a relatively small distance apart and sliding into separate parallel grooves along the shell wall, whereby substantially tight joints will be formed between the plates and the wall and a substantial dead fluid space will be formed between the plates.
